US00D833979S

(12) **United States Design Patent** (10) Patent No.: **US D833,979 S**
(45) Date of Patent: **** Nov. 20, 2018**

(54) **ELECTRICAL CONTACT PIN**

(71) Applicant: **DELTA ELECTRONICS, INC.**,
Taoyuan (TW)

(72) Inventors: **Ruei-Lin Hung**, Taoyuan (TW);
Hung-Sheng Hsieh, Taoyuan (TW)

(73) Assignee: **DELTA ELECTRONICS, INC.**,
Taoyuan (TW)

(**) Term: **15 Years**

(21) Appl. No.: **29/627,061**

(22) Filed: **Nov. 22, 2017**

(51) LOC (11) Cl. **13-03**
(52) U.S. Cl. ....

(57) **CLAIM**

The ornamental design for an electrical contact pin, as shown and described.

DESCRIPTION

FIG. 1 is a perspective view of a first embodiment of an electrical contact pin showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a perspective view showing the use status of the electrical contact pin;
FIG. 9 is a perspective view of a second embodiment of an electrical contact pin showing our new design;
FIG. 10 is a front elevational view thereof;
FIG. 11 is a rear elevational view thereof;
FIG. 12 is a left side elevational view thereof;
FIG. 13 is a right side elevational view thereof;
FIG. 14 is a top plan view thereof;
FIG. 15 is a bottom plan view thereof; and,
FIG. 16 is a perspective view showing the use status of the electrical contact pin.

In the drawings, the dash-dot line represents the boundary of the claimed design, the broken lines are for the purpose of illustrating portions of the electrical contact pin and form no part of the claimed design.

1 Claim, 12 Drawing Sheets
